UNITED STATES PATENT OFFICE

WALTER E. SHAVER, OF SCHENECTADY, NEW YORK

CHROMATIC PLAYING ATTACHMENT FOR HARMONICAS

Application filed May 25, 1929. Serial No. 866,037.

This invention relates to musical instruments of the harmonica type, and has for one of its objects to provide an instrument of this character on which may be performed a piece of music written in any key.

The invention has for a further object to provide a musical instrument of the character stated which shall embody a mouth piece, a pair of harmonicas of which one is one-half tone higher than the other, and a valve through the medium of which an operative relation may be easily and quickly established between the mouth piece and either of the harmonicas.

15 The invention has for a further object to provide a musical instrument of the character stated wherein the mouth piece and valve shall constitute a chromatic playing attachment, and wherein such attachment shall be so constructed as to permit two differently keyed harmonicas to be readily and quickly secured in operative relation therewith.

20 The invention has for a further object to provide a musical instrument of the character stated wherein the chromatic playing attachment and the harmonicas shall be detachably connected together so as to permit the harmonicas to be removed and others in 25 different keys substituted therefor.

25 The invention has for a further object to provide a musical instrument of the character stated wherein the chromatic playing attachment shall be simple, durable and efficient, and capable of being manufactured and sold at low cost.

With the foregoing and other objects in view, the nature of which will appear as the description proceeds, the invention consists 30 in the construction, combination and arrangement of parts hereinafter fully described and claimed, and illustrated in the accompanying drawings, wherein:—

40 Figure 1 is a view in front elevation of a musical instrument embodying my invention;

45 Figure 2 is a view partly in end elevation and partly in vertical section of the instrument;

50 Figure 3 is a sectional view taken on the

vertical plane indicated by the line 3—3 of Figure 1;

Figure 4 is a sectional view taken on the horizontal planes indicated by the line 4—4 of Figure 3;

55 Figure 5 is a sectional view taken on the vertical plane indicated by the line 5—5 of Figure 3;

Figure 6 is an elevational view of one of the bars for detachably securing harmonicas to the chromatic playing attachment;

Figure 7 is a view partly in end elevation and partly in vertical section illustrating a slightly modified form of the means for operating the valve plate of the chromatic playing attachment;

Figure 8 is an elevational view of the modified form of one of the parts of the chromatic playing attachment; and

Figure 9 is a sectional view of such part.

The chromatic playing attachment comprises a mouth piece 1 which is of elongated formation in plan and may be made from wood or metal or any other suitable material.

The mouth piece 1 is provided with orifices 2 extending horizontally therethrough and corresponding in number to the air passages in the harmonicas in connection with which the attachment is to be used.

A plate 3 is arranged at the front side of the mouth piece 1, and is greater in width than the mouth piece and extends beyond the sides thereof.

The plate 3 is provided with parallel rows of orifices 4 and 5, which extend longitudinally thereof and aligned with the orifices 2 in the mouth piece 1.

The plate 3 is provided at its longitudinal edges with forwardly extending flanges 6 which contact with a plate 7 arranged forwardly of the plate 3 and provided with parallel rows of

orifices 8 and 9 registering with the orifices 4 and 5.

The plate 3 is provided at its ends with notches 10 and 11, and the plate 7 is provided at one of its ends with a notch 12, which registers with the notch 10.

The plates 3 and 7 are preferably made from metal and constitute a casing for a valve plate 13. The valve plate 13 is equal in length to the valve casing plates 3 and 7, and it is smaller transversely than the valve

casing plates, so as to permit it to be moved transversely of the valve casing.

The valve plate 13 is provided with a single row of orifices 14 which extends longitudinally thereof.

In one adjusted position of the valve plate 13, the row of orifices 14 registers with the rows of orifices 4 and 8, and in the other adjusted position of the valve plate, the row of orifices 14 registers with the rows of orifices 5 and 9.

A base 15 is arranged beyond the valve casing plate 7, and it may be made from wood or metal or other suitable material. The base 15 is provided with a longitudinally extending row of passages 16, which register with the orifices 8 in the valve casing plate 7, and the base is provided with a longitudinally extending row of passages 17, which register with the orifices 9 in the valve casing plate 7. The passages 16 and 17 are of angular formation and extend transversely of the base 15 from points close to the longitudinal center of the base to points close to the longitudinal edges of the base. The base 15 is provided at its ends with notches 18 and 19. The notch 19 registers with notch 11 in the valve casing plate 3, and the notch 19 registers with the notches 10 and 12 in the valve casing plates 3 and 7.

The mouth piece 1, the valve casing plates 3 and 7 and the base 15 are secured in assembled relation by machine screws 20. The valve plate 13 is provided with transversely extending slots 21 for the passage of the screws 20 and for the reception of washers 20^a loose on the screws between the valve casing plates 3 and 7. The washers 20^a are slightly thicker than the valve plate 13, in order that they may function to maintain the valve casing plates 3 and 7 spaced sufficiently to insure the free movement or operation of the valve plate. The washers 20^a contact with the side walls of the slots 21 and due thereto function to prevent any longitudinal displacement of the valve plate with respect to the valve casing. A plate 15^a is secured to the forward side of the base 15 by the screws 20. This plate is provided with a row of orifices 15^b registering with the passages 16, and a row of orifices 15^c registering with the passages 17.

Two harmonicas 22 and 23, in different keys, are employed in connection with the chromatic playing attachment, and they are arranged with the forward ends of their air passages in registration with the lower ends of the orifices 15^b and 15^c, respectively, in the plate 15^a. To prevent the leakage of air between the plate 15^a and the harmonicas 22 and 23, a gasket 24 is arranged between these parts. The gasket 24 may be made from rubber, leather or other suitable material, is cemented or otherwise secured to the plate 15^a, and is provided with longitudinally ar-

ranged rows of orifices 24^a registering with the orifices 15^b and 15^c in the plate and with the passages in the harmonicas.

The harmonicas are detachably secured to the chromatic playing attachment by means comprising bracket plates 25 which extend forwardly from the ends of the plate 15^a and are secured thereto by the screws 20. The brackets 25 are provided with inturned front ends 26, which contact with the sides of the plate 15^a and are apertured for the reception of the screws 20. The angular ends 26 of the brackets 25 are provided at their terminals with rearwardly extending flanges 27 which contact with the longitudinal edges of the plate 15^a to hold the brackets against turning movement with respect to the plate. The brackets 25 are each provided with a pair of relatively spaced inner flanges 28, and with a pair of similar flanges 29. The harmonica 22 has its ends arranged between the pairs of flanges 28 and the harmonica 23 has its ends arranged between the pairs of flanges 29, the brackets 25 and their flanges holding the harmonicas against any longitudinal or lateral movement with respect to the chromatic playing attachment.

The means for detachably securing the harmonicas to the chromatic playing attachment also comprises bars 30 which extend across the front edges of the harmonicas, and coil springs 31 which are arranged between the harmonicas and secured to the plates and to a shaft 32 rockably supported in bearing openings 33 formed in the front ends of the brackets 25. When it is desired to remove the harmonicas and substitute therefor new ones in the same or different keys, it is only necessary to swing the bars 30 laterally beyond the brackets 25, and in view thereof the substitution may be easily and quickly accomplished.

To permit it to be used for the purpose of moving the valve plate 13 from one of its positions to the other, the shaft 32 is provided at its ends with arms 33 which extend rearwardly through the notches 10, 11, 12, 18 and 19 in the valve casing plates 3 and 7 and base 15, and through openings 34 in the ends of the valve plate 13. A push rod 35 is arranged at one end of the chromatic playing attachment for sliding movement transversely thereof, and is provided with an opening 36 for the reception of one of the shaft arms 33. The push rod 35 is arranged between the valve casing plate 3 and the base 15, and to permit this arrangement of the push rod, the valve casing plate 7 is made slightly shorter than the valve casing plate 3. The push rod 35 extends in any position thereof beyond both sides of the chromatic playing attachment, and the ends thereof are turned forwardly to provide finger pieces 37.

The push rod 35 is provided at its outer side with a forwardly extending flange 38

130

which contacts with the adjacent end edge of the base 15 to hold the push rod against tilting movement on the shaft arm to which it is connected. The push rod provides means through the medium of which the valve plate 13 may be easily and quickly moved from one of its positions to the other.

A cover 39 for the harmonicas is detachably connected to the base 15. It is made of metal, and is of substantial U-form in cross section. The front edges of the sides of the cover 39 are provided with inturned flanges 40, which engage in grooves 41 formed in and extending longitudinally of the side edges of the base 15. The cover 39 may be applied or removed by moving it in endwise direction with respect to the chromatic playing attachment.

As shown in Figure 8, the harmonica brackets are connected by a plate 25^a which is provided with tapped openings 42 for the reception of the lower end through the screws 20. This plate is provided with longitudinally extending rows of orifices 43 and 44, which register with the openings in the base 15 and in the harmonicas, the brackets being designated 25^b in this figure.

In Figure 7, a modified form of the means for rocking the valve plate adjusting shaft 32 is shown. This means comprises a flattened push bar 35^a slidably mounted between the valve casing plate 3 and the base 15 and provided at one end with a head 45. In this form of the invention means are provided for yieldingly holding the valve plate 13 in one of its positions, and this means comprises a spring 46 secured to the harmonica brackets into one of the shaft arms 33.

It should be understood from the foregoing description, taken in connection with the accompanying drawings, that the attachment permits any piece of music to be played by harmonicas, that the valve plate normally establishes communication between the mouth piece and one only of the harmonicas, and that the valve plate may be easily and quickly adjusted to establish communication between the mouth piece and the other harmonica and adjusted to re-establish communication between the mouth piece and said first harmonica.

While I have described the principle of the invention, together with the structure which I now consider to be the preferred embodiment thereof, I wish it understood that the structure shown is merely illustrative, and that such changes may be made therein when desired, as fall within the scope of the invention as claimed. In this connection it is to be understood that, while the harmonica playing attachment is illustrated and described as being adapted for use in connection with harmonicas of the single reed type, it is also adapted for use in connection with harmonicas of the double reed

type, and to adapt it for use in such harmonicas, it is only necessary to provide the valve plate and the lower valve casing plate with two additional rows of orifices and to provide the base and base plate with two additional rows of passages.

I claim:—

1. A musical instrument of the character set forth, comprising a mouth piece, harmonicas of different tones and arranged in spaced parallel relation, and means adjustable for establishing communication between the mouth piece and either of the harmonicas.

2. A musical instrument of the character set forth, comprising a mouth piece provided with orifices, harmonicas, a valve casing positioned between the mouth piece and harmonicas and provided with rows of orifices communicating with the orifices in the mouth piece and communicating respectively with the air passages in the respective harmonicas, a valve plate arranged within the valve casing and adjustable for closing either row of said orifices, a rock shaft provided with arms engaging the valve plate, and means for rocking the shaft to adjust the valve plate.

3. A musical instrument of the character set forth, comprising a mouth piece provided with orifices, harmonicas, a valve casing positioned between the mouth piece and harmonicas and provided with rows of orifices communicating with the orifices in the mouth piece and communicating respectively with the air passages in the respective harmonicas, a valve plate arranged within the valve casing and adjustable for closing either row of said orifices, a rock shaft provided with arms engaging the valve plate, and means yieldingly holding the valve plate in one of its positions.

4. A chromatic playing attachment for harmonicas, comprising a mouth piece provided with orifices, a base provided with a plurality of rows of passages, a valve plate provided with a row of orifices and mounted between the mouth piece and base for adjustment to arrange its orifices in registration with the orifices in the mouth piece and one of the rows of passages in the base, a shaft rockably supported on the base and provided with arms engaging the valve plate, and a push rod slidably mounted between the mouth piece and base and connected to one of said rods.

5. A chromatic playing attachment for harmonicas, comprising a mouth piece provided with orifices, a base provided with a plurality of rows of passages, a valve plate provided with a row of orifices and mounted between the mouth piece and base for adjustment to arrange its orifices in registration with the orifices in the mouth piece

and one of the rows of passages in the base, a shaft rockably supported on the base and provided with arms engaging the valve plate, and a push rod slidably mounted between the mouth piece and base and connected to one of said rods, said push rod being provided with downwardly extending terminals and with a flange contacting with an end of the base.

6. A musical instrument of the character set forth, comprising a chromatic playing attachment, harmonicas, and means for detachably securing the harmonicas in relatively spaced relation to the attachment.

7. A musical instrument of the character set forth, comprising a chromatic playing attachment, brackets secured to the attachment, harmonicas having their ends engaged with the brackets, and spring pressed means secured to the attachment and engaging the harmonicas to detachably secure the attachment and harmonicas together.

8. A musical instrument of the character set forth, comprising a chromatic playing attachment, harmonicas, means detachably connecting the attachment and harmonicas, and a cover for the harmonicas detachably connected to the attachment.

9. A chromatic playing attachment for harmonicas, comprising a mouth piece provided with orifices, a base provided with rows of passages, valve casing plates positioned between the mouth piece and base, a valve plate arranged between the valve casing plates and provided with orifices and transverse slots, attaching elements for securing the mouth piece base and valve casing plates in assembled relation, said elements passing through the slots and the valve plate, and washers mounted upon the elements and arranged within the slots, the washers being thicker than the valve plate to maintain the valve casing plates in proper spaced relation.

10. A chromatic playing attachment for harmonicas, comprising a mouth piece provided with orifices, a base provided with rows of passages, valve casing plates positioned between the mouth piece and base, a valve plate arranged between the valve casing plates and provided with orifices and transverse slots, attaching elements for securing the mouth piece base and valve casing plates in assembled relation, said elements passing through the slots and the valve plates, and washers mounted upon the elements and arranged within the slots, the washers being thicker than the valve plate to maintain the valve casing plates in proper spaced relation and the washers contacting with the side walls of the slots to prevent longitudinal displacement of the valve plate.

11. A chromatic playing attachment for harmonicas, comprising a mouth piece provided with a longitudinal row of orifices, a valve casing secured to and communicat-

ing with the mouth piece and provided with two longitudinal rows of orifices, a valve plate narrower than and arranged in the casing, said valve plate being provided with a single longitudinal row of orifices and adjustable transversely of the casing to cover one row of said first orifices and to arrange its orifices in registration with the other row of said first orifices, and means for adjusting the valve plate.

In testimony whereof I hereunto affix my signature.

WALTER E. SHAVER.
